US0D1048686S

(12) United States Design Patent (10) Patent No.: US D1,048,686 S
(45) Date of Patent:  Oct. 29, 2024

(54) INSOLE

(71) Applicants: Zhuangli Qin, Xiaogan (CN);
Zhengjun Lv, Yichang (CN)

(72) Inventors: Zhuangli Qin, Xiaogan (CN);
Zhengjun Lv, Yichang (CN)

() Term: 15 Years

(21) Appl. No.: 35/519,797

(22) Filed: Dec. 21, 2023

(80) Hague Agreement Data

Int. Filing Date: Dec. 21, 2023

Int. Reg. No.: DM/234555

Int. Reg. Date: Dec. 21, 2023

Int. Reg. Pub. Date: Jan. 26, 2024

(51) LOC (14) Cl. 02-04

(52) U.S. Cl.

USPC D2/961

(58) Field of Classification Search
